C. T. WESTLAKE AND C. S. SHALLENBERGER.
DRAW BAR YOKE;
APPLICATION FILED MAR. 4, 1918.

1,357,603.

Patented Nov. 2, 1920.

UNITED STATES PATENT OFFICE.

CHARLES T. WESTLAKE AND CHARLES S. SHALLENBERGER, OF ST. LOUIS, MISSOURI,
ASSIGNORS TO TRANSMOM DRAFT GEAR COMPANY, OF ST. LOUIS, MISSOURI, A COR-
PORATION OF DELAWARE.

DRAW-BAR YOKE.

1,357,603.

Specification of Letters Patent.

Patented Nov. 2, 1920.

Application filed March 4, 1918. Serial No. 220,204.

To all whom it may concern:

Be it known that we, CHARLES T. WESTLAKE and CHARLES S. SHALLENBERGER, citizens of the United States, residing at St. Louis, Missouri, have invented a certain new and useful Improvement in Draw-Bar Yokes, of which the following is a full, clear, and exact description, such as will enable others skilled in the art to which it appertains to make and use the same, reference being had to the accompanying drawings, forming part of this specification.

Our invention relates generally to railway car construction and more particularly to a yoke or connection between a coupler draw-bar and a draw-bar extension, the latter usually being a part of the draft rigging.

The principal objects of our invention are, to generally improve upon the existing types of yokes or connections between the draw-bars and extensions, and to provide a relatively simple, inexpensive and efficient construction having great strength and durability and which will enable the coupler draw-bar and extension to be quickly and conveniently connected, and likewise disconnected when removal, displacement, or repairs are necessary.

With the foregoing and other objects in view, our invention consists in certain novel features of construction and arrangement of parts, hereinafter more fully described and claimed, and illustrated in the accompanying drawings, in which—

Figure 1 is an elevational view of our improved yoke in position upon a draw-bar and extension with a portion of said yoke broken away.

Fig. 2 is a plan view of the yoke connection in position on the adjacent ends of a draw-bar and extension.

Fig. 3 is a horizontal section taken approximately on the line 3—3 of Fig. 1.

Fig. 4 is a cross section taken approximately on the line 4—4 of Fig. 2.

Fig. 5 is a cross section taken approximately on the line 5—5 of Fig. 2.

Referring by numerals to the accompanying drawings, 10 designates a coupler shank or draw-bar and 11 an extension or draft member which is usually a part of the transom draft gear. The coupler shank 10 which is of the usual construction is pro-

vided near its rear end and on both top and bottom with transversely disposed shoulders 12.

The yoke or connection contemplated by our invention is made in two parts or halves which are adapted to combine with each other to form a readily assembled or separable housing which practically incloses the adjacent ends of the shank 10 and extension 11.

The halves are identical in size and construction and each comprises a horizontally disposed plate 13 with the sides of which are formed integral a pair of side plates 14 and 15, the latter being arranged parallel with each other and disposed at right angles to the plane occupied by plate 13. Portions 70 of these side plates 14 and 15 are extended beyond the end of the horizontal plate 13 as designated by 16 and formed through these extensions are slots 17 which are adapted to receive a key 18, the latter passing 75 through a suitable opening formed in the outer end of extension 11.

Formed integral with one end of the plate 13 and disposed between the ends of side plates 14 and 15 opposite the ends provided 80 with the extension 16 is a transversely disposed flange 19, the inner face of which bears directly against the corresponding shoulder 12 on the shank 10 when the two-part yoke or connection is assembled for use.

Projecting outwardly from the end of each side wall 14 opposite the end provided with the extension 16 is a longitudinally disposed rib or lug 20 and when the halves of the yoke are properly assembled, these 90 lugs or ribs 20 occupy horizontally disposed slots or recesses 21 which latter are formed in housings 22, the latter being formed integral with the side plates 15.

In order that the halves of the yoke may 95 be properly assembled, vertically disposed notches or openings 23 are formed in the housings 22, said openings leading into the rear portions of the grooves or recesses 21 and enabling the ribs or flanges 20 to pass 100 into said slots or recesses.

When the halves of the yoke are properly assembled, as illustrated in the drawing, the side wall 15 which is integral with the plate 13 lying on top of the adjacent ends of the shank 10 and extension 11, overlies side

wall 14 which is integral with the plate 13 beneath said shank and extension, and on the opposite side of the connection the side wall 15 which is integral with the lower 5 one of the plates 18 overlies the side plate 14 which is integral with the upper plate 13. When so assembled, the ribs or lugs 20 occupy the grooves or recesses 21 in housings 22, thereby effectually preventing the halves 10 of the yoke from separating vertically and in order to firmly secure the parts in position, a bolt 24 is inserted through suitable apertures formed in the plates 13 and through the rear end of shank 10.

15 The pulling strains impressed on shank 10 are transmitted to the two parts of the yoke by the shoulders 12 which engage directly against the shoulders or inner faces of the flanges 19 and these strains are transmitted 20 from the two parts of the yoke to the extension 11 through key 18. This key which practically holds the halves of the yoke in assembled relation is preferably provided on one end with a head 18^a and the 25 opposite end being provided with a series of apertures 18^b which are adapted to receive a cotter pin or the like and which latter holds the key in place.

The distance from the rear end of the 30 coupler shank 10 to the shoulders 12 frequently varies on the same shank and in order to insure the uniformity of transmittal of pulling strains between the two parts of the yoke upon the shoulders 12 thus located, the slots 17 which accommodate the 35 width of the key so that in such cases, said key 18 are made slightly longer than the key may tilt slightly in one direction or the other and still hold the halves of the yoke 40 in positions with the flanges 19 bearing directly against shoulders 12.

In assembling the halves of the yoke or connection, one half is placed slightly in advance of the other or in position so that 45 the lugs 20 on the oppositely arranged side walls 14 will enter the openings 23 and after this operation has been completed, the halves are shifted lengthwise relative to each other for a short distance, thereby moving 50 the lugs or flanges 20 into the notches or recesses 21.

The key 18 is now inserted through the openings 17 and through the aperture in extension 11 after which bolt 24 is inserted 55 through plates 13 and shank 10.

It will be understood that the interengaging connection between the overlapping parts of the yoke serves to retain the parts of the yoke in assembled relation upon the 60 draw-bar and that the bolt 24 is only used as an auxiliary securing means to hold the parts of the yoke together in the event that key 18 should become displaced, and which action might permit the halves of the yoke 65 to shift lengthwise relative to each other a

sufficient distance to separate and detach themselves from the end of coupler shank.

A yoke connection of our improved construction can be easily assembled and applied for use, provides a strong, rigid and substantial connection between the draw-bar shank and extension, can be readily removed to facilitate repairs or renewal of parts, and is very effective in transmitting pulling and buffing stresses from the coupler shank to 75 the extension and vice versa.

It will be readily understood that minor changes in the size, form and construction of the various parts of our improved yoke connection may be made and substituted for 80 those herein shown and described, without departing from the spirit of our invention, the scope of which is set forth in the appended claims.

We claim:

1. The combination with a draw-bar and draw-bar extension, of a yoke for connecting said draw-bar and extension, said yoke comprising a pair of interchangeable members having pairs of overlapping side walls, 90 one wall of each pair being provided with a substantially L-shaped slot and the companion wall of said pair being provided with an elongated lug which is adapted to enter the vertically disposed portion of the 95 slot in the adjacent wall when the members are moved toward each other and to occupy the horizontally disposed portion of said slot when one member is moved longitudinally with respect to the other. 100

2. The combination with a draw-bar and draw-bar extension, of a yoke for connecting said draw-bar and extension, said yoke comprising a pair of interchangeable members having pairs of overlapping side walls, 105 one wall of each pair being provided with a substantially L-shaped slot and the companion wall of said pair being provided with an elongated lug which is adapted to enter the vertically disposed portion of the 110 slot in the adjacent wall when the members are moved toward each other and to occupy the horizontally disposed portion of said slot when one member is moved longitudinally with respect to the other, and there being internally disposed shoulders formed on said members, which shoulders are adapted to engage corresponding shoulders on the engaged draw-bar. 115

3. The combination with a draw-bar and draw-bar extension, of a yoke for connecting said draw-bar and extension, said yoke comprising a pair of interchangeable members having pairs of overlapping side walls, 120 one wall of each pair being provided with a substantially L-shaped slot and the companion wall of said pair being provided with an elongated lug which is adapted to enter the vertically disposed portion of the 125 slot in the adjacent wall when the members 130

are moved toward each other and to occupy the horizontally disposed portion of said slot when one member is moved longitudinally with respect to the other, and said 5 overlapping walls being provided with registering key openings.

4. The combination with a draw-bar and draw-bar extension, of a yoke for connecting said draw-bar and extension, said yoke 10 comprising a pair of interchangeable members having pairs of overlapping side walls, one wall of each pair being provided with a substantially L-shaped slot and the companion wall of said pair being provided 15 with an elongated lug which is adapted to enter the vertically disposed portion of the slot in the adjacent wall when the members are moved toward each other and to occupy the horizontally disposed portion of said slot 20 when one member is moved longitudinally with respect to the other, there being internally disposed shoulders formed on said members, which shoulders are adapted to engage corresponding shoulders on the engaged draw-bar, and said overlapping walls being provided with registering key openings.

5. In a connecting yoke of the class described, a pair of interchangeable members, 30 each of which comprises a pair of connected side walls, one wall of each member being provided on its inner face with a substantially L-shaped slot, the horizontal leg of which is elongated and longitudinally disposed, and the other wall being provided with an elongated longitudinally disposed outwardly 35 projecting portion which is adapted to engage in the slot of the companion member when said members are moved toward each other and one member moved longitudinally relative to the other, and there being an internally disposed shoulder formed on each member between the side walls thereof.

moved toward each other and one member 40 moved longitudinally relative to the other.

6. In a connecting yoke of the class described, a pair of interchangeable members, each of which comprises a pair of connected side walls, one wall of each member being 45 provided on its inner face with a substantially L-shaped slot, the horizontal leg of which is elongated and longitudinally disposed, the other wall being provided with an elongated longitudinally disposed outwardly 50 projecting portion which is adapted to engage in the slot of the companion member when said members are moved toward each other and one member moved longitudinally relative to the other, and there being registering key openings formed in said side walls.

7. In a connecting yoke of the class described, a pair of interchangeable members, each of which comprises a pair of connected 60 side walls, one wall of each member being provided on its inner face with a substantially L-shaped slot, the horizontal leg of which is elongated and longitudinally disposed, the other wall being provided with an 65 elongated longitudinally disposed outwardly projecting portion which is adapted to engage in the slot of the companion member when said members are moved toward each other and one member moved longitudinally 70 relative to the other, and there being an internally disposed shoulder formed on each member between the side walls thereof.

In testimony whereof we hereunto affix our signatures this 27th day of February, 75 1918.

CHARLES T. WESTLAKE.
CHARLES S. SHALLENBERGER.
